BRAKE OPERATING MEANS

Carl Egon Alma, Vienna, Austria, and Heinrich Egen, Essen, Germany, assignors to Fried Krupp Aktiengesellschaft, Essen, Germany, a corporation of Germany

Application June 3, 1932, Serial No. 615,150
In Germany August 19, 1931

11 Claims. (Cl. 188—148)

This invention relates to brake operating means for railway trains.

In applying the brakes of a long train from the locomotive, the individual brakes of the cars are not operated simultaneously, but successively, with the result that the brakes of the last car are operated at an interval after the application of the brakes of the first car. As a result, the rear cars of the train which have not had their brakes applied bump into the cars ahead, the speed of which has been reduced by application of their brakes. The resulting thrusts arising in the cars in the rear section of the train as a result of this action, may prove dangerous to the cars.

An object of this invention is the provision of automatically actuated means for operating the brakes of a car when its draft gear is subjected to strains exceeding predetermined value.

Other objects, novel features and advantages of this invention will be apparent from the following specification and accompanying drawings, wherein:

Fig. 1 is a longitudinal section of an embodiment of the invention, and

Fig. 2 is a view similar to Fig. 1 in another position of the parts.

In the drawings only the essential elements of a railway draft gear are disclosed, the non-essentials being eliminated for the sake of clarity. The draft gear for each car comprises two rods A extending longitudinally of the car frame, each rod being substantially one-half the length of the car and each rod being provided with a coupler head a'. Each rod A is provided with a pair of collars a² and a³ against which abut followers B, slidably mounted on the rod A. Springs C are interposed between the followers B and transmit strains from the rods A to the car structure in the well-known manner through abutments provided on the car frame for that purpose. Near its inner end each rod A has a collar a⁴ rigidly mounted thereon and followers D are slidably mounted on the rods A between the collar a⁴ and abutments a⁵ provided at the inner end of each rod. A spring E is arranged between the followers D and is of higher resistance than the springs C. Guide rods F extend through each collar a⁴ and the followers D, these rods being provided with nuts so that outward pull on either rod A is transmitted through the followers D, rods F and spring E to the remaining rod A.

Levers G are pivoted at one end to the collars a⁴ and are pivotally connected at their other

end by a pin g' carrying a roller g², thus forming a toggle for moving the roller g² upon relative movement of the collars a⁴. A bell crank lever H is pivotally supported on the car frame by a pin h³ and has its arm h' extending into the path of the roller g². The arm h² of the lever H is provided with a shoulder which is engaged by one arm of the lever K, also supported by the under frame of the car. This lever K is attached to a valve T controlling a branch conduit l' leading from the air brake line L and discharging to the atmosphere. A link M is pivoted to the arm h¹ and is provided at its free end with a slot m¹ through which projects a pin k¹ carried by the lever K.

On the link M there is provided a collar m² and a follower N is attached to the pin k¹, a spring P being arranged between the follower N and the collar m². A pull rod R is attached to the lever K for actuating the same.

In normal train operation, the parts are in the position shown in Fig. 1, the spring P being under compression and the valve T being closed. The bell crank lever H is pressed toward the roller g² by the spring P, the rotation of the bell crank lever being limited by engagement of the arm h² with the abutment S on the car frame. Assume now, that inward push is applied on both rods A due to the fact that the brakes of the front cars of the train have been applied, but the brakes in the rear cars have not been applied. The spring E is compressed by the forces applied to the rod A which move toward each other to bring the abutments a⁵ into engagement. As the collars a⁴ move toward each other, the levers G move the roller g² into engagement with the arm h¹ and when the abutments a⁵ are brought into engagement with each other, the bell crank lever H is rocked to release the lever K, which is forced by the spring P from the position shown in Fig. 1 to the position shown in Fig. 2, thereby turning the valve T to open the branch conduit l' to atmosphere and effect operation of the brakes. The parts may be returned to the position shown in Fig. 1, merely by pulling the rod R.

Also it is obvious that by connecting the levers G to the followers D, instead of the collars a⁴, the brakes may be applied upon excessive draft strains as distinguished from excessive buffering strains, such as previously referred to in description of the operation of the device.

Furthermore, it is to be understood that various modifications may be made in the structure above described, without in any way de-

parting from the spirit of the invention as defined in the accompanying claims.

We claim:

1. In combination, a car having a draft gear 5 extending the full length thereof and comprising two relatively movable sections, a lost motion connection between the inner ends of said sections for transmitting pulling and buffing strains from one to the other, an air brake line, 10 a valve therefor, and means controlled by relative movement of said sections for actuating said valve.
2. In combination, a draft gear having two relatively movable sections, an air brake line, a 15 valve therefor, resilient means tending to open said valve, detent means for holding said valve in closed position, and means actuated by relative movement of said sections for releasing said detent.
3. In combination, a car having a draft gear 20 extending the full length thereof and comprising two relatively movable sections, a lost motion connection between the inner ends of said sections for transmitting pulling and buffing strains from one to the other, resilient means 25 tending to oppose relative movement of said sections, an air brake line, a valve therefor and means controlled by relative movement of said sections for actuating said valve.
4. In combination, a draft gear having two 30 relatively movable sections, an air brake line, a valve therefor, and a toggle connecting said relatively movable sections, and means controlled by said toggle for actuating said valve.
5. In combination, a draft gear having two 35 relatively movable sections, resilient means tending to oppose relative movement of said sections, an air brake line, a valve therefor, and a toggle connecting said relatively movable sections, and means controlled by said toggle for actuating said valve.
6. In combination, a draft gear having two 40 relatively movable sections, an air brake line, a valve therefor, resilient means tending to open said valve, detent means for holding said valve in closed position, and a toggle connecting said sections and movable into engagement with said detent to release the same.
7. In combination, a draft gear having two 45 relatively movable sections, an air brake line, a valve therefor, a valve lever, a bell crank lever having a shoulder on one arm to engage said valve lever to hold the valve in closed position, resilient means interposed between the second arm of the bell 50 crank lever and said valve lever to open the valve when said valve lever is released by said detent, and a toggle carried by said sections, said toggle being movable into engagement with the second arm of the bell 55 crank lever to rock the same and release said valve lever.
8. In combination, a draft gear having two relatively movable sections, resilient means tending to oppose relative movement of said sections, an air brake line, a valve therefor, resilient means tending to open said valve, detent means for holding said valve in closed position, and a toggle connecting said sections and movable into engagement with said detent to release the same.
9. In combination, a draft gear having two relatively movable sections, resilient means tending to oppose relative movement of said sections, an air brake line, a valve therefor, a valve lever, a bell crank lever having a shoulder on one arm to engage said valve lever to hold the valve in closed position, resilient means interposed between the second arm of the bell 60 crank lever and said valve lever to open the valve when said valve lever is released by said detent, and a toggle carried by said sections, said toggle being movable into engagement with the second arm of the bell 65 crank lever to rock the same and release said valve lever.
10. In combination, a draft gear having two relatively movable sections, an air brake line, a valve therefor, a valve lever, a bell crank lever having a shoulder on one arm to engage said valve lever to hold the valve in closed position, a link pivoted to the second arm of the bell crank lever and having a pin and slot connection at its other end with said valve lever, an abutment 70 on said link, resilient means interposed between said abutment and said valve lever, and a toggle carried by said sections, said toggle being movable into engagement with the second arm of the bell 75 crank lever to rock the same and release said valve lever.
11. In combination, a draft gear having two relatively movable sections, resilient means tending to oppose relative movement of said sections, an air brake line, a valve therefor, a valve lever, a bell crank lever having a shoulder on one arm to engage said valve lever to hold the valve in closed position, a link pivoted to the second arm of the bell crank lever and having a pin and slot connection at its other end with said valve lever, an abutment on said link, resilient means interposed between said abutment and said valve lever, and a toggle carried by said sections, said toggle being movable into engagement with the second arm of the bell 80 crank lever to rock the same and release said valve lever.
